UNITED STATES PATENT OFFICE

171,307

PIVOTED TRAY HOLDER

George H. Philp, Wheatridge, Colo.

Application November 12, 1952, Serial No. 22,233

Term of patent 14 years

(Cl. D44—29)

To all whom it may concern:

Be it known that I, George H. Philp, a citizen of the United States of America, residing at Wheatridge, in the county of Jefferson and State of Colorado, have invented a new, original, and ornamental Design for a Pivoted Tray Holder, of which the following is a specification, reference being had to the accompanying drawing, forming a part hereof.

In the drawing:

Fig. 1 is a perspective view of a pivoted tray holder, showing my new design; and

Fig. 2 is a side view thereof.

I claim:

The ornamental design for a pivoted tray holder, as shown.

GEORGE H. PHILP.
